LAG COMPENSATING DEVICE

Paul Kollsman, Woodhaven, N. Y.

Application August 3, 1929, Serial No. 383,407

14 Claims. (Cl. 73—4)

This invention relates to lag compensating devices, and has among its objects the provision of a device of the character described, having improved counteracting means to eliminate the effect of elastic hysteresis from spring systems.

Another object of this invention is the provision of an improved device of the nature set forth which is particularly applicable to aneroid diaphragms, barometers or altimeters.

Another object of the invention is to provide improved means embodying the principle of springs subject to hysteresis effects upon deformation thereof and consisting of materials of different specific hysteresis, and the hysteresis effects of the springs being neutralized by counteracting hysteresis effects of the same magnitude of the springs, with the resultant effect that the useful motion of the springs is substantially free of hysteresis effects at least for a short or initial time period as upon occurrence of the deformations of the springs.

A further object of the invention is to provide an improved device of the type mentioned which is of simplified and inexpensive construction, simple and reliable in operation, and efficient in use to a high degree.

Other objects and advantages of the invention will become apparent as the specification proceeds.

With the aforesaid objects in view, the invention consists in the novel combinations and arrangements of parts hereinafter described in their preferred embodiments, pointed out in the subjoined claims, and illustrated on the annexed drawing, wherein like parts are designated by the same reference characters throughout the several views.

In the drawing:

Figure 1 is a view in side elevation of a device embodying the invention, with parts in section to show the construction.

Fig. 2 is a plan view of the same, with parts omitted.

Figs. 3 to 5 are views in side elevation of modified forms of the invention.

Generally described, the invention provides a device for wholly or partly eliminating the effect of hysteresis in spring systems. By this invention, the compensating spring changes its shape as a result of the deformation of the main spring or aneroid, but since the form and characteristics of the two springs are different, a change in pressure exerted on the springs will cause a major resultant movement in one direction or in the opposite direction to actuate an in-

dicator member. When, however, the major resultant movement shall have been completed and hysteresis effects of the two springs take place, the effect of hysteresis of the compensating spring neutralizes the hysteresis effects of the main spring with the resultant effect of no actuation of the pointer. This is so because the form and characteristics of the springs are so chosen that they will have substantially the same results from hysteresis but in opposition to each other in the organizations disclosed. The invention may be practiced in various forms, but basically includes a main spring and a compensating spring. To further define the invention, if the same is embodied in an indicator, the reading thereof is preferably taken practically at the instant of a marked change in the condition shown by the indicator. The materials of the springs are chosen so that the specific elastic hysteresis or lag per unit of time of the springs may be made zero or positive or negative, consistent with the arrangements of the springs, the simplest arrangements utilizing materials of different specific hysteresis, with hysteresis effect of the main spring caused by a stress applied thereto being neutralized by a counteracting hysteresis effect of substantially the same magnitude of the compensating spring, the result being that hysteresis effects are eliminated from the spring system either wholly or for a short period of time upon completion of the useful motion. The invention is not to be limited to any particular location of the compensating spring, as the principle herein defined includes rather the coaction of the springs as broadly defined, and, furthermore, it is applicable to any kind of pressure responsive box. While the material of the compensating spring may have a greater or lesser specific hysteresis or lag per unit of time than that of the main spring, and the latter a movement over a different range than the compensating spring, yet the invention may also be practiced by using main spring portions and an intermediate compensating spring moving as a unit, provided that the lag per unit of time of the compensating spring is approximately equal to the sum of the lags per unit of time of the main spring portions, with the lags opposed to equal zero.

The advantages of the invention as here outlined are best realized when all of its features and instrumentalities are combined in one and the same structure, but, useful devices may be produced embodying less than the whole.

It will be obvious to those skilled in the art to which this invention appertains, that the same

may be incorporated in several different constructions. The accompanying drawing, therefore, is submitted merely as showing the preferred exemplifications of the invention.

5 Referring in detail to the drawing, in Figs. 1 and 2, 10 denotes a device embodying the invention. The same includes an aneroid diaphragm 11 mounted in any suitable manner, as, for example, on a support 12. The aneroid may be 10 variously formed, and one or both sides 13, 14 thereof may be concaved as shown, and are preferably made of a metal of low specific hysteresis or lag per unit of time. To define the invention, the side 14 may be called the main spring.

15 Coacting with the main spring, which may be made of phosphor bronze is a compensating spring 16 which is made of a material such as zinc of high specific hysteresis. The said compensating spring is curved oppositely to the main spring and is connected to the main spring at points 16 within the boundary of the latter. The connections at 16 may be of any suitable type whether rigid or pivotal. The compensating spring may be of elongated, or other form. 20 When considered with reference to the longitudinal direction of the compensating spring, the main spring may be said to have ends at 17. Connected to the compensating spring is a link 18 which operates a pointer 19, the position of 25 which can be read on a scale 20.

30 In operation, it is seen that when the diaphragm responds to a decrease of pressure, the main spring tends to move into a plane, and hence to straighten the compensating spring 16. 35 Since the main spring is longer than the compensating spring, the movement of the main spring is greater than that of the compensating spring, thus deflecting the pointer. Now the main spring continues its movement due to the hysteresis, but the lag per unit of time thereof is counteracted by that of the compensating spring. As the material of the latter has a high specific hysteresis compared with a material in the main spring of a low specific hysteresis in 40 approximate inverse proportion to the movements of the respective springs, the lag of the device may be wholly or substantially neutralized, for the few initial seconds during which lag occurs. Thereafter the time element of hysteresis may affect the pointer reading, but the 45 object of this invention is to permit accurate and practically immediate reading of an instrument. After sufficient time has elapsed for all lag to disappear, the instrument will again read 50 accurately.

55 In Fig. 3 is shown a modification of the invention in which the aneroid capsule 21 is of a slightly different form, and the compensating spring 16 is rigidly connected to a side wall of 60 the same by means of arms 22, thus spacing the compensating spring from the main spring. Relative adjustability may be provided between the main spring and the compensating spring, for example, by changing the curvature or length 65 of the latter. This may be accomplished in various ways as, for instance, by securing the compensating spring to the arms 22 with screws 22a that pass through slots 15a in the compensating spring, the screws being threaded into 70 the said arms. To adjust the compensating spring it is merely necessary to loosen the screws and deflect the spring into the desired shape after which the screws are tightened. In all other respects, this modification functions like 75 the device 10.

In Fig. 4 is shown another modification of the invention, wherein the aneroid 23 has centrally connected to one or both opposite walls thereof at 24 any suitable leaf spring 25, or the like, of a material of low specific hysteresis, which may be in the nature of a loop, the long sides of 5 which may extend approximately at right angles to the axis of the aneroid. The compensating spring 16 consisting of material of high specific hysteresis may be connected to the spring 25 at 10 any suitable points therealong, as, for instance at 26. It is noted that in this arrangement, the compensating spring coacts indirectly with the aneroid main spring, an intermediate member or spring being provided. Accordingly, 15 the compensating spring may have a large range of variation in its length relation to the main spring; it may be considerably longer with respect to the diameter of the aneroid, permitting any corresponding change in its hysteresis effect, 20 so long as the motions of the main and compensating springs neutralize according to the mode of operation hereinbefore described. Among the advantages of this form of the invention may be mentioned that the aneroid may 25 act at a single point 24; furthermore, the entire spring area of the aneroid is effective for useful motion.

In Fig. 5 is shown a further modification of the invention in which a compensating spring 30 27 coacts with an aneroid or spring 28 at a single point without the use of an intermediate spring. The spring 27 may be of any suitable form, for instance, in the nature of a tension coil spring. One end of the spring 27 is connected to the 35 aneroid at 28, and its other end 38 is connected to any co-operating spring such as a leaf spring 31 at an end of the same, the other end being secured to a support 32. Since the compensating spring is under tension, the spring 31 is constantly under a certain stress. The compensating spring may consist of a material having a high specific hysteresis, and the spring 31 may consist of material of a low specific hysteresis. 40 Since springs 28 and 31 have similar specific 45 hysteresis, they may be considered as parts of a main spring means, and particularly so where, as in this case, both of these springs have stationary mountings and are thus permanently 50 interrelated as a unit.

In operation, when the atmospheric pressure on the aneroid capsule is relieved, the same expands, and may therefore be considered as moving upward. Hence the tension on the springs 27 and 31 is correspondingly relieved, so that the 55 spring 31 is caused to move upward. The spring 27 likewise is caused to move upward but contracts slightly due to the diminished tension. At or soon after the instant that this motion is completed, as for a rapid and marked change of the atmospheric pressure, the specific hysteresis or lag per unit of the materials of the different 60 springs occurs, with resultant counteracting hysteresis effects of substantially equal magnitude of the springs. Thus the motion of the 65 aneroid capsule now continues as before, further relieving the stresses on the springs 31 and 27, the spring 31 tending to move to the same degree as the aneroid capsule, because the specific hysteresis of the materials or both is as nearly as 70 possible the same. However, as the material of the spring 27 has a higher specific hysteresis, it tends to contract faster in proportion to the lagging motions of the springs 28 and 31. Hence 75 it creates a proportionately greater tension be-

tween the springs 28 and 31, and since the spring 31 is naturally weaker than the spring 28, the spring 31 is deflected downward against its lagging tendency and to a degree directly determined by whatever might be the specific hysteresis of the material of the spring 27. Hence the hysteresis effects counteract each other and the total lag of the system is diminished. If it be desired not merely to decrease the lag of the 5 spring system, but to reduce it substantially to zero, then the lag per unit of time of the material of the spring 27 must equal substantially the sum of that of the springs 28 and 31. In other words, assume that the lag per unit of time were 10 equal for the materials of the three springs, the lags for the springs 27 and 31 would merely counterbalance each other, so that the lagging motion of the spring 28 would not be affected. But if the lag per unit of time of the material 15 of spring 27 is equal to the sum of those for the springs 28 and 31, then the hysteresis effect, or at least the total lag per unit of time for the system may be made approximately zero. In actual practise the closeness with which the result is 20 attained, depends merely upon the degree of care 25 employed by the trial and error method in designing the system, scraping down one or more of the springs, and the like. It will ordinarily suffice to slightly change the size or shape of either of the springs 27 or 31 until, by proper calibration, 30 it is seen that the instrument reads accurately at the time or instant after occurrence of a sudden rapid change in the stress of the system. Hence it may be said that by this invention the 35 "instantaneous effect" of hysteresis is eliminated, substantially instantaneously compensated for, or neutralized, and an accurate instantaneous reading obtained. In each case herein the compensating spring, such as 15 and 27 may be made 40 of zinc, and the main spring or main spring assembly such as 23 and 25, and 28 and 31 of phosphor bronze.

I claim:

1. A device including a main plate spring, and 45 a compensating plate spring smaller than the main spring, said springs being curved in opposite directions, the compensating spring being connected at its ends to the main spring to move with the deformation of the main spring and to 50 be caused to deform as a result of such deformation of the main spring, the deformation of the compensating spring being thus smaller than that of the main spring, and the hysteresis effects of the compensating spring being equal to and 55 counteracting the hysteresis effects of the main spring for eliminating the substantially instantaneous effect of hysteresis from the device.
2. A device including a pressure responsive diaphragm, a curved main plate spring centrally 60 connected to the diaphragm, the end portions of said spring being relatively fixed, a compensating spring curved in opposite relation of the main spring, said compensating spring being shorter than the main spring and consisting of a ma- 65 terial having a higher specific hysteresis than the material of the main spring, said compensating spring being connected to the main spring to be deformed by the latter as a result of the deformation of the main spring by the diaphragm, 70 and an indicator coacting with the compensating spring, the pressure responsive diaphragm being subject, upon changes of stress applied to the same, to a hysteresis effect neutralized by a counteracting hysteresis effect of substantially 75 the same magnitude of the springs whereby the

springs compensate for the specific hysteresis of the diaphragm to produce an accurate instantaneous indication by said indicating means of the action of said diaphragm.

3. A device having an indicator and springs of different form and characteristics including a main spring means, and a compensating spring means, said spring means being interconnected so that the force of the compensating spring means is adapted to act counter to that of the main spring means, with a deformation in the main spring means directly causing a deformation in the compensating spring means, said spring means being so different from each other that a change in pressure exerted on both spring means will cause a major resultant movement in one direction or in an opposite direction to actuate the indicator, and the material of the different spring means each having a specific hysteresis different than that of the other, and the spring means being so related to each other that the hysteresis effect of the compensating spring means is in opposition to and neutralizes that of the main spring means with the resultant effect of no actuation of the indicator from hysteresis 25 effects.

4. In an indicator device, a spring system comprising a single resilient main spring sensitive to gaseous pressure, and a compensating spring, said main and compensating springs being interconnected so that a deformation of the main spring causes an opposing deformation of the compensating spring, said springs being so different from each other that a change in pressure exerted on the main spring will cause a major resultant movement in one or in an opposite direction of the spring system to actuate an indicator, and the different springs each having a specific hysteresis different than that of the other, 30 and the springs being so related to each other than the hysteresis effects of the compensating spring act in opposition to and neutralize those of the main spring.

5. A device including a pressure responsive diaphragm of a material having a low specific hysteresis, a compensating spring of a material of high specific hysteresis connected thereto, and a fixed spring of a material of low specific hysteresis connected to the compensating spring independently of the diaphragm to continuously exert a stress thereon, so that the hysteresis effect of the pressure responsive diaphragm and fixed spring, caused by a change in stress applied to the same, is neutralized by a counteracting hysteresis effect of the same magnitude of the compensating spring, and an indicator coacting with the springs and diaphragm to indicate the performance of the latter without the initial effect of lag.

6. A device including a spring system instantaneously compensated for hysteresis, said system having a main spring subject to hysteresis effect upon changes of stress applied thereto, a compensating spring of a material having a different specific hysteresis than the material of the main spring and being so arranged relative thereto as to counteract the specific hysteresis of the main spring, and resilient means of a material having a specific hysteresis similar to that of the main spring, said resilient means being connected to one of the springs and causing a stress to be exerted to deform the compensating spring, the said hysteresis effect of the main spring and resilient means being neutralized by an equal 75

- counteracting hysteresis effect of the compensating spring.
7. A spring system substantially instantaneously compensated for hysteresis, including a stress receiving main spring subject to hysteresis effect upon changes of stress applied thereto, means connected thereto for counteracting the hysteresis effect of the main spring, said means including a compensating spring of a material having a different specific hysteresis than that of the main spring, and a resilient member of a material having a specific hysteresis similar to that of the main spring, said member being connected to the compensating spring and said means being so arranged relative to the main spring as to be movable in the same general direction therewith with the resilient member maintaining a stress on the compensating spring, with the said hysteresis effect of the main spring and resilient member being neutralized by an equal counteracting hysteresis effect of said means.
8. A spring system substantially instantaneously compensated for hysteresis including a main spring subject to hysteresis effect upon changes of stress applied thereto, a compensating spring connected at one end thereto, and a third spring connected to the opposite end of the compensating spring for continually exerting a stress thereon, the main and third springs consisting of material having a specific hysteresis of similar degree, the compensating spring consisting of a material having a different specific hysteresis than said main and third springs, and the hysteresis effect of the main spring and third spring being neutralized by a substantially equal counteracting hysteresis effect of the compensating spring.
9. A spring system substantially instantaneously compensated for hysteresis including a main spring subject to hysteresis effect upon changes of stress applied thereto, a bowed compensating spring of a material having a different specific hysteresis than that of the main spring, and an intermediate oppositely bowed spring of a material having a specific hysteresis similar to that of the main spring, the intermediate spring being connected to the ends of the compensating spring and to the main spring in spaced relation to said ends so that the intermediate spring under actuation of the main spring changes the curvature of the compensating spring, and the compensating spring being arranged to deform in a different direction than the main spring, with the hysteresis effect of the main spring being neutralized by a counteracting substantially equal hysteresis effect of the compensating spring.
10. A spring system substantially instantaneously compensated for hysteresis including an expansible diaphragm subject to hysteresis effect upon changes in stress applied thereto, a leaf spring connected at a point to said diaphragm, and a bowed compensating spring connected at its ends to the leaf spring, the latter being of a material having a specific hysteresis similar to that of the material of the main spring, the compensating spring being of a material having a different specific hysteresis than that of the main

spring, the compensating spring being deformed by deformation of the leaf spring under actuation of the main spring with the deformation of the compensating spring occurring in opposite direction relative to that of the main spring, and the hysteresis effect of the diaphragm being neutralized by a substantially equal counteracting hysteresis effect of the other springs.

11. A device including a pressure responsive spring diaphragm, and a compensating spring of a material having a different specific hysteresis than that of said diaphragm and being adapted to deflect in a different direction in a different degree than said diaphragm, the compensating spring being connected at its ends to the diaphragm so that a deflection of the diaphragm causes a deflection of the compensating spring in approximately inverse proportion to the specific hysteresis of the different springs, and the hysteresis effect of the diaphragm being neutralized by an equal counteracting hysteresis effect of the compensating spring.

12. A spring system having a useful motion substantially instantaneously compensated for hysteresis, including a main spring means, a compensating spring of a material having a different specific hysteresis than that of the main spring means, the main spring means having opposed portions connected to the ends of the compensating spring so that the latter is subject to deformations of the main spring means, and the hysteresis effect of the main spring means being neutralized by a counteracting substantially equal hysteresis effect of the compensating spring.

13. A spring system having useful motion of the type disclosed, comprising a main spring means, an elongated compensating spring, the ends of the compensating spring being connected to the main spring means so that the latter acts on the compensating spring in opposed relation and subjects the same to the deformations of the main spring means, and the effects of the hysteresis of the compensating spring upon deformation being substantially equal and opposite to the effects of hysteresis of the main spring means, whereby the spring system is substantially instantaneously compensated for hysteresis.

14. A device having a spring system substantially instantaneously compensated for hysteresis, including a main spring means subject to hysteresis effect upon changes of stress applied thereto, a compensating spring of a material having a relatively high specific hysteresis, the main spring means having portions of a material having a relatively low specific hysteresis, the compensating spring having its ends connected to the main spring portions so as to be stressed thereby and to be responsive to deformations of the main spring portions, and the compensating spring having a lesser range of motion than the main spring means, with the hysteresis effect of the main spring means being neutralized by a substantially equal and counteracting hysteresis effect of the compensating spring.

PAUL KOLLMAN.
